UNITED STATES PATENT OFFICE.

SAYERS B. LAMKIN, OF DAWSON, TERRITORY OF NEW MEXICO.

HAND FOR COMPTOMETERS.

957,221.

Specification of Letters Patent. Patented May 10, 1910.

Application filed November 1, 1909. Serial No. 525,814.

To all whom it may concern:

Be it known that I, SAYERS B. LAMKIN, of Dawson, in the county of Colfax and Territory of New Mexico, have invented 5 certain new and useful Improvements in Hands for Comptometers; and I hereby declare that the following is a full, clear, and exact description thereof, reference being had to the accompanying drawings, which

10 form part of this specification.

This invention is a novel device for use with "comptometers", or like calculating machines, to facilitate operations thereon; its object being to provide a mechanical 15 assistant or "hand" for the operator wherewith he can perform operations on the machine with great rapidity, and with absolute accuracy so far as certain series of repeated key manipulating operations are 20 concerned.

The "hand" is simple, and inexpensive; and will lessen the amount of finger work of the operator; and is readily adaptable for use with various kinds and makes of calculating 25 machines.

I will explain the invention as embodied in the "hand" device illustrated in the accompanying drawings, which is particularly designed and adapted for use with a 30 comptometer having ten vertical columns of nine keys numbered 1 to 9 inclusive. Each column having separate calculating and additive carrying mechanism. The size of "hand" should be varied to correspond with 35 size of comptometer—(the size of calculating machine designated by the number of vertical columns).

I term the device a "hand", and it consists generally of a plate or frame, provided 40 with a series of rows of holes or sockets in its under side,—corresponding in location and arrangement with the series of rows of keys in each set in the key-board of the machine,—and with a handle on its upper 45 side by which it can be easily grasped and manipulated by the operator. The hand is also provided with removable pins which can be placed in the sockets corresponding to the keys it is desired to simultaneously 50 depress, and after suitably arranging the pins, the operator places the "hand" over the key-board of the machine, and presses it thereupon, thereby causing the set pins to simultaneously depress the corresponding

keys, and perform at one operation of the 55 "hand" a number of finger operations; the pins performing the work of the operator's fingers; and when any given series of keys has to be repeatedly operated in making calculations, the advantages of the "hand" 60 over finger manipulation of the keys will be obvious.

I will explain the invention in detail with reference to the accompanying drawings, and set forth in the claims the essential 65 features of the invention for which I desire protection.

In said drawings—Figure 1 is a top view of an ordinary comptometer key-board and showing the "hand" in operative position 70 thereover, partly in section and partly in dotted lines. Fig. 2 is a bottom plan view of the "hand." Fig. 3 is an enlarged side view of the "hand" as in operation. Fig. 4 is a perspective view of the "hand" de- 75 tached; and Fig. 5 is a detail sectional view of the "hand".

The "hand", as shown, comprises a plate 1, provided on its under side with a series of rows of sockets 1^a, the number of rows of 80 sockets, and the number of sockets in a row, corresponding exactly with the number of rows of keys, and number of keys in a row, of the key-board of the comptometer or calculating machine with which the "hand" is 85 to be used. As shown there are nine rows of sockets, and ten sockets in a row. The sockets are numbered correspondingly to the keys of the machine, but in reverse order, and with the digits in large figures in line 90 with the sockets, and the co-digits in smaller figures above and to left of the digits; see Fig. 2. The complete "hand" as shown comprises the base plate and its attachments; and ten pins, one for each row of keys. 95 Preferably the sockets for the even digits may be a sixteenth of an inch deeper than the sockets for the odd digits, to compensate for the concaved keys on odd digits of the comptometer, and enable the pins, herein- 100 after referred to, to be made of equal length.

A set of pins 2 is provided, each adapted to be detachably attached to the board by having its shank stuck into any of the sockets, as shown. The pins may be of about one and one-fourth inches in length, and have their shanks formed to fit snugly in the sockets so that the pins will not drop out of place; the

outer portions of the pins may be milled or roughened as indicated at 2^a, to facilitate their insertion and removal from the sockets; and they are preferably provided with 5 rubber tips 2^b on their outer ends, so as to cushion their contact with the keys, and lessen shock and noise. The pins may be of aluminum or other suitable metal and the sockets may be bushed with aluminum or 10 other suitable metal if desired.

The base is provided at its upper edge, and under side, with a flange 3, and at its left-hand edge and under side, with a flange 3^a, which flanges assist in correctly positioning 15 the "hand" over the key-board of the machine; and when the upper flange 3 is brought against the side of the top row of keys on the machine, and the side flange against the side of the left-hand row of keys, 20 all the pins are positioned accurately over the corresponding keys, (see Figs. 1 and 3) so that by thus locating and then depressing the "hand", the proper keys will be simultaneously operated.

25 The "hand" has a handle 4 on its top side, by which it can be readily manipulated. The utility and mode of using the "hand" will be clearly understood from the following examples.

30 Operation: The "hand" is not designed to be used in the ordinary simple multiplying and dividing operations on the comptometer, although it can be used for any example large or small; but it is particularly adapted for long multiplication and division computations, such as in railroad-operating statements, in ascertaining cost per train mile against operating expenses, and their hundreds of sub-accounts where a 35 common divisor is used; or in mining calculation, in ascertaining the cost per ton of coal mined against the various operating expenses; or cost per ton of coke made against the various expenses. In such accountings 40 the divisors are frequently in the hundreds of thousands, and can very seldom be simultaneously reached with the fingers, and never with swiftness and accuracy; and for this reason special rules have been devised for 45 accomplishing division on the comptometer, when the divisor is of four or more digits, and even their work is very slow and tedious. With my "hand" however a divisor of ten 50 places can be worked just as rapidly and accurately as a divisor of two digits. It is preferable to figure such division computations by using a reciprocal and multiplying, as multiplication can be done on the comptometer faster than division, and the "hand" 55 is invaluable in such work. As an example of the utility of the "hand" assume the divisor to be 2,236,217.48 and the reciprocal is .0000004471836961; set the reciprocal (4471836961) in the "hand", as per rules 60 governing the comptometer (see Fig. 2) and

set the decimal point on the register as usual—then proceed with multiplication as usual, assuming the items to be as follows, viz:

Expense items.	Cost.	70
\$16,654.91	.00744780	
672.57	.00030076	
854.72	.00038222	
1,184.59	.00050737	
2,284.79	.00102172	75
1,921.89	.00085944	
4,272.18	.00191045	
6,211.89	.00277786	
42.50	.00001900	
189.00	.00008452	80
172.65	.00007721	
\$34,411.69	.01538835	

The reciprocal set into the hand forms the 85 multiplicand and the expense items the multiplier. The first item computes a cost of 7 mills against say repairs to track; next item computes .0003 against repairs to bridges, and so on arriving at a total cost of .0154 against 90 say operating account maintenance of way. Generally only four decimal figures are shown in a statement; but to be absolutely accurate the extra decimals may be figured to determine the correct fourth decimal. In 95 the foregoing example the decimals are carried to the extreme of ten counting digits in the reciprocal (16 places) to show what the "hand" can accomplish in one shift. Eight significant terms in the reciprocal is what 100 is generally used, but I can operate up to ten digits as readily as any less number. Of course for smaller key-boards, the "hand" could be made smaller, the feature thereof being that it is provided with sockets corresponding in number and arrangement with the keys of the key-board of the machine; and with a pin for each row of sockets. After the operator sets up the reciprocal on the "hand" by adjusting the proper number 105 of pins in the proper rows; all he has to do in entering the reciprocal on the machine, is to press the "hand" down upon the key-board and he can perform this operation rapidly, without any mental worry as to its 110 accuracy, and without tiring his fingers, and with no possibility of error if he accurately sets the pins in the "hand" at the outset.

In working division or multiplication, the operator should set up the divisor or multiplicand, respectively, in the "hand" and proceed in the usual manner. For example, if the quotient of 382561.47 and 897449 be required, set up the multiplicand in the "hand," beginning with 3 at the right and working to the left; this when inverted will make the 382 fall over the first three columns to left of the machine. Strike the keys eight times, with the "hand;" then move "hand" one column to right, which 125 130

will place the partition side between the first two columns to left of machine, and strike nine times. Then move "hand" one column to right, and strike seven times; etc. until all 5 digits of multiplier have been used; pointing off in the usual way. Since multiplication is easier to accomplish on the comptometer than division it is often advantageous to work up a set of division computations by 10 multiplication and when one divisor is common to several or numerous dividends, such as ascertaining (in railroad work) cost per freight train mile against the hundreds of freight operating expenses, it is an easy matter to find a reciprocal, or how many times 15 the divisor is contained into \$1.00 and multiplying such reciprocal by the various expenses. After finding the reciprocal set it up in the "hand" as already explained, 20 set your decimal pointer on comptometer behind the required decimal and use figures to left of such pointer. If cost is required to four places, it is not necessary to work out your reciprocal to more than six significant 25 terms. In corporation accounting, however, many straight division computations are required of long dimensions such as ascertaining percentage of operating expenses to earnings, etc. For example say the earnings for 30 a certain period amounts to \$318,198.65 against operating expenses amounting to \$237,548.72. Strike off the dividend on machine according to the digits (large figures) beginning at the extreme left, causing 35 237548.72 to appear on the register. Set up the divisor in the "hand" according to the co-digits (small figures) beginning from extreme right column of "hand" and working to left, which when inverted will throw the 40 318 directly over the 237. Since 318 is not contained into 237 move the "hand" one column to right letting partition board slip between first and second columns of keys, then 2 being the first figure to left of "hand" 45 strike twice with the "hand" and keep on striking until the number of strokes agree with that figure which was formerly 2,— then, without shifting to next column, keep on striking until the register shows a number smaller than 318; then shift to the next 50 column which will place partition board of "hand" between the second and third columns of comptometer, and proceed as before; and so on through the series, and the 55 register will show .7465219 (quotient)— 29739565 (remainder)—or .7465 answer. It is of course not necessary to carry out operations to such extremes for practical purposes but they should be carried out six decimals for absolute accuracy. An idea of how 60 much time may be saved by using the "hand" in such computations can be gained by working out this example on a ten column comptometer to .7465422, and applying special rule laid down for division when divisor is

over four places; it takes about one-hundred and eleven finger operations to work the example out seven places. With the "hand" it will require only thirty strokes. Time is also saved in manipulating the fingers for 70 new trial divisors. When using the "hand" the divisor being set up, no manipulating is necessary. Another great advantage in using the "hand" is that it is not so trying on the eyes and brain of the operator, as all 75 he has to think about is how many times to strike; and since he does not have to manipulate the keys in any way, he can work out computations in multiplication and division very rapidly. 80

Having described my invention what I claim as new and desire to secure by Letters Patent thereon is:

1. A key-operating attachment for comptometers and the like, comprising a plate 85 provided with a plurality of sockets on one face corresponding in arrangement with the keys of the machine, and a smaller number of adjustable pins adapted to be placed in any of said sockets and whereby predetermined keys of the machine may be simultaneously operated by manually placing the plate over the keys and depressing the same. 90

2. A key-operating attachment for comptometers and the like comprising a "hand" 95 consisting of a plate provided with a series of rows of sockets on one face corresponding in arrangement with a set of keys on a machine, and depending flanges on its under side whereby the plate may be properly positioned over the keys; with adjustable pins adapted to be removably engaged in any of said sockets whereby the predetermined keys on the machine may be simultaneously operated by placing the plate over the keys 100 and depressing same. 105

3. A key-operating attachment for comptometers and the like comprising a plate having a plurality of rows of sockets on its under side corresponding in arrangement with the keys on the machine, said sockets being numbered correspondingly with the keys, and depending flanges on the lower face and top and side of the plate whereby it may be correctly positioned 110 over the keys previous to depression thereof; with a set of removable pins each adapted to be detachably secured in any one of the sockets. 115

4. A key-operating attachment for comptometers and the like comprising a mechanical "hand" having a plurality of rows of sockets on its under side corresponding in number and arrangement with the keys on the machine, said sockets being numbered 120 correspondingly with the keys; a handle on the top of the "hand" opposite the sockets whereby it may be manipulated by hand, and means on the lower face of the "hand" whereby it may be correctly positioned over 125 130

the keys previous to depression thereof; with removable pins adapted to be detachably secured in any of the sockets.

5. A key-operating attachment for comptometers and the like comprising a mechanical "hand" having a plurality of sockets on its under side corresponding in arrangement with the keys on the machine; a set of removable pins each adapted to be detachably secured in any of the sockets, said pins having rubber tips on their outer ends, and the sockets corresponding to the concaved keys on the comptometer being shallower than the other sockets.

10 15 6. A manually operable key-operating attachment for comptometers and the like comprising a plate having rows of sockets on its under side corresponding in arrange-

ment with the keys on the machine, said sockets being numbered correspondingly 20 with the keys; a handle on the side of the plate whereby it may be manipulated by hand, and flanges on the lower side of the plate whereby it may be correctly positioned over the keys previous to depression thereof; with a set of removable pins each adapted to be detachably secured in any one of the sockets, and having rubber tips on their outer ends.

25 In testimony that I claim the foregoing 30 as my own, I affix my signature in presence of two witnesses.
